UNITED STATES PATENT OFFICE.

JOHN F. COURSON, OF PITCAIRN, PENNSYLVANIA.

DRAFT-GEAR.

1,247,085.

Specification of Letters Patent. Patented Nov. 20, 1917.

Application filed March 28, 1917. Serial No. 157,885.

To all whom it may concern:

Be it known that I, JOHN F. COURSON, a citizen of the United States, residing at Pitcairn, in the county of Allegheny and State of Pennsylvania, have invented certain new and useful Improvements in Draft-Gears, of which the following is a specification.

My invention is an improvement in draft gears of the class utilizing spring resistance, and is designed to provide for the absorption of the shocks of buffing and pulling strains by means of annular springs, and co-acting mechanism, as hereinafter described.

The present invention is similar in theory of operation to that disclosed in my pending application filed December 18, 1916, Serial No. 137,496. In the present application I provide a pair of annular springs embracing longitudinally movable members operable in one direction or the other by pressure of a single transverse key connected with the draw bar. The annular springs are located one at each side of the draw bar and embrace the movement-imparting mechanism which is engaged by the key at each side of the draw bar, the key extending through the central sills at each side beyond and being mounted in reinforced slots therein. The gear effects elongation of the springs in one direction or the other in buffing or pulling, whereby the sides of the springs are changed in position inwardly toward the longitudinal center of the gear and with a resulting increase of resistance proportional to the strain, effecting a resulting reaction and desirable resistance.

Preferred constructions of the invention are shown in the accompanying drawings, in which:-

Figure 1 is a longitudinal vertical sectional view through a complete gear as assembled in normal relaxed position, indicated by the line I, I, of Fig. 2.

Fig. 2 is a longitudinal horizontal section on the line II, II, of Fig. 1.

Fig. 3 is a view similar to Fig. 1, but showing the spring elongated under action of buffing strains.

Fig. 4 is a cross section on the line IV, IV, of Fig. 1.

Fig. 5 is a cross section on the line V, V, of Fig. 1. 55

Fig. 6 is a detail perspective view of the sliding stop block.

Fig. 7 is a similar view of one of the center sill abutment plates.

Fig. 8 is a similar view of one of the terminal bearing cap members for the key block.

Fig. 9 is a view similar to Fig. 1, but showing a modified construction.

Fig. 10 is a longitudinal horizontal sectional view indicated by the line X, X, of Fig. 9.

Fig. 11 is a view similar to Fig. 9 showing the spring elongated under buffing strains, as in Fig. 3. 70

Fig. 12 is a transverse sectional view on the line XIII, XIII, of Fig. 9.

Fig. 13 is a perspective detail view of one of the sliding stop blocks.

Fig. 14 is a similar view of one of the center sill abutments.

In the drawings, 2 represents the draw bar of the coupler connected with the laterally arranged sliding stop blocks 3 by a transverse bolt or key 4, engaging holes 5 thereof. The sliding stop blocks 3, which are generally rectangular in construction, are slidably mounted between the abutment lugs 6, 6, of the center sill abutment plate 7. Said plate as shown is riveted to the inner side of each center sill 8 and is provided with a longitudinal clearance slot 9 coinciding with a similar slot 9' in the center sill. It will be understood that the abutment lugs 6 may be of other construction as, for instance, the form shown in modified construction illustrated on Sheet 2 of the drawings, or otherwise. I do not therefore wish to be restricted to the particular manner of making them integral with the single plate 7, as shown, although such form is good construction and provides for the definite spacing of the abutment lugs and their fixed connection with the under frame.

When made in the form shown, plate 7 may be provided with a closed-end slot at its rear portion whereby to provide additional reinforcement for the center sills under such buffing strains as are sufficient to carry the key 4 clear back to the ends of the slots. 90

The other end of the slot may be open as 95

100

105

shown, or closed at both ends if desired, the reduced strains in pulling not requiring any unusual reinforcement.

For the purpose of providing reduced bearings for the inner end portions of the tension springs, I provide the bearing caps 10 having upper and lower abutting lip portions 11—11 fitting over the ends of the sliding stop blocks 3 and movable therewith 10 away from the abutment lugs 6, under action of key 4.

The terminals of lips 11 bear inwardly against lugs 6 in normal position, providing resisting engagement for one set of the bearing caps or the other, dependent upon the direction of strain.

The active shock absorbing element of the gear is an annular spring 12 of one or more continuous bands of suitable resilient material such as steel and which is of circular or oval form as shown in Figs. 1 and 3. The spring as thus made embraces the rounded ends of bearing caps 10 and surrounds the intervening mechanism, preferably under some reduced tension in normal position.

The outer portion of each center sill 8 is preferably reinforced by a suitable abutment member as a plate 13, which may conform 30 generally to the shape of the base plate 7, having a corresponding central slot, and may be conveniently connected therewith and with the center sill members by rivets as shown.

35 The construction and operation of the gear will be readily understood by all those familiar with this class of mechanism. In action, either in buffing or pulling, draw bar 2 and key 4, which slidably rests in the slots 40 of the center sill and the abutment plate, moves the sliding stop block 3 either rearwardly or forwardly, correspondingly moving one bearing cap 10 and elongating the spring 12, the other bearing cap, of course, 45 resting fixedly against the abutments 6. The construction is such as to facilitate immediate return of the parts to normal position upon release of pressure, the active power of the spring increasing in proportion to the 50 degree of movement in buffing or pulling, and tending to resume its circular form upon termination of such strains.

In Figs. 9, 10 and 11, I show a modified construction of parts in which the draw bar 2^a is connected by a transverse bolt or key 4^a with the oppositely located sliding stop blocks 3^a, 3^a, engaging the inner endmost grooves or recesses 5^a thereof. The stop blocks in such construction are independently separable and each provided with a rounded terminal 10^a, preferably integral therewith, the blocks being provided at their upper and lower inner portions with longitudinal slide-ways 3^{aa} adapted to fit and slide 65 upon the stop abutments 6^a. These abut-

ments, as shown in Fig. 14, are of rectangular bar construction, riveted to the center sills 8^a by rivets 7^a above and below the central portion of the gear. With either arrangement of abutments 6 or 6^a the sliding 70 stop block 3 or blocks 3^a are housed in such a manner as to provide for good support, compact construction and free action in the manner described.

Annular springs 12^a embrace the longitudinally separable portions of the gear, as thus arranged, each spring engaging by its opposite inner end portions the rounded ends 10^a of separable blocks 3^a.

The operation of the gear is substantially 80 the same as above described, *i. e.* movement of the draw bar and key in either direction operating to press the two opposite sliding blocks 3^a together away from their relatively stationary companion blocks and from the 85 resisting abutments 6^a.

The mechanism is preferably located somewhat rearwardly of the end sill of the under frame, whereby to provide for ample space and facility of erection or taking apart, and 90 it will be observed that the several parts of the gear, other than the fixedly attached portions, may be applied or removed by merely withdrawing the single transverse key 4 or 4^a.

The construction is comparatively simple, comprising few parts, it is not liable to get out of order, and the gear has a high efficiency or resisting action under the continuous heavy shocks incident to the usual 100 traffic movements. The invention may be changed or modified by the skilled mechanic in different details, proportions, design, or in other respects, but all such changes are to be considered as within the scope of the 105 following claims.

What I claim is:—

1. In a gear, a pair of separable bearing members, an intervening abutment therefor, means for moving one bearing member away 110 from the other, and an annular spring embracing said members.

2. In a gear, a pair of separable bearing members, an intervening abutment therefor, means for moving one bearing member away 115 from the abutment, and an annular spring embracing said members.

3. In a gear, a pair of separable bearing members, an intervening abutment therefor, a sliding block engageable with either 120 of said bearing members, actuating means engaging said block, and an annular spring embracing said members.

4. In a gear, a pair of separable bearing members, an intervening abutment therefor, 125 a sliding block engageable with either of said bearing members, resilient means for opposing the separation of the bearing members, a draw bar, and a key connecting the drawbar with the sliding block.

5. In a gear, a continuous annular spring, a pair of separable tension exerting members engaging the spring at opposite inner portions, an intervening resisting abutment 5 for said members, a sliding block engaging each of said members, and means engaging said block operable to move it in either direction.
6. In a gear, a continuous annular spring, 10 a pair of separable tension exerting members engaging the spring at opposite inner portions, an intervening resisting abutment for said members, a sliding block engaging each of said members, a drawbar, and a key 15 connecting the drawbar with the sliding block.
7. In a gear, oppositely arranged sets of pairs of separable bearing members, abutments between the members of each pair of 20 bearing members, means for moving the bearing members at one side of said abutments away from the members at the other side thereof, and an annular spring embracing each pair of bearing members.
- 25 8. In a gear, oppositely arranged sets of pairs of separable bearing members, abutments between the members of each pair of bearing members, means for moving the bearing members at one side of said abutments away from said abutments and an 30 annular spring embracing each pair of bearing members.
9. In a gear, oppositely arranged sets of pairs of separable bearing members, abutments between the members of each pair of bearing members, a pair of sliding blocks 35 engageable with either bearing member at each side, actuating means engaging said blocks, and an annular spring embracing 40 each pair of bearing members.
10. In a gear, oppositely arranged sets of pairs of separable bearing members, abutments between the members of each pair of bearing members, a pair of sliding blocks 45 engageable with either bearing member at each side, resilient means for opposing the separation of the bearing members, a drawbar, and a key connecting the drawbar with the sliding blocks.
- 50 11. In a gear, a pair of continuous annular springs, oppositely located sets of pairs of separable tension exerting members engaging the springs at opposite inner portions, intervening resisting abutments for 55 said members, sliding blocks engaging said members, and means engaging said blocks operable to move them in either direction.
12. In a gear, a pair of continuous annular springs, oppositely located sets of pairs 60 of separable tension exerting members engaging the springs at opposite inner portions, intervening resisting abutments for
- said members, sliding blocks engaging said members, a drawbar, and a key connecting the drawbar with the sliding blocks. 65
13. In combination, longitudinally slotted center sills, inwardly extending abutments secured thereto, oppositely movable spring actuating members adapted to engage said abutments and to be moved away therefrom 70 by a transverse key, annular springs embracing said members, a drawbar, and a transverse key extending therethrough and through the slotted sills.
14. In combination, longitudinally slotted center sills, inwardly extending abutments secured thereto, oppositely movable spring actuating members having stop portions extending toward said abutments, annular springs embracing said members, a drawbar, 75 and a transverse key extending therethrough and between the spring actuating members and through the slotted center sills. 80
15. In combination with center sills having inwardly extending bearing abutments 85 and clearance slots, a drawbar, a transverse key extending therethrough and into said slots, sliding blocks on said key, spring bearing caps on said blocks arranged to engage said abutments and annular springs embracing said bearing caps. 90
16. In combination, longitudinally slotted center sills, inwardly extending abutments secured thereto, inner center sill reinforcing portions, oppositely movable spring actuating members having stop portions extending toward said abutments, annular springs embracing said members, a drawbar, and a transverse key extending therethrough and between the spring actuating 95 members and through the slotted center sills. 100
17. In combination, longitudinally slotted center sills, inwardly extending abutments secured thereto, inner and outer center sill reinforcing portions, oppositely movable spring actuating members having stop portions extending toward said abutments, annular springs embracing said members, a drawbar, and a transverse key extending therethrough and between the spring actuating members and through the slotted center sills. 105
18. In combination, longitudinally slotted center sills, inwardly extending abutments secured thereto, spring actuating members 110 movable between said abutments by a transverse key, annular springs embracing said members, a drawbar, and a transverse key extending therethrough and through the slotted sills. 115
- 120 In testimony whereof I hereunto affix my signature.

JOHN F. COURSON.
